UNITED STATES PATENT OFFICE

ADIEL Y. DODGE, OF SOUTH BEND, INDIANA

ONE-WAY REACTANCE DEVICE

Application filed September 29, 1930. Serial No. 484,972.

My invention relates to reactance devices. One of the objects of my invention is to provide an improved reversible one way reactance device of the type in which a flexible strap or spring is wrapped about a rotatable shaft and so designed as to permit rotation of the shaft in one direction and prevent rotation in the opposite direction and in which the action of the clutch may be reversed.

10 Further objects will appear from the description in the claims.

In the drawings, in which two embodiments of my invention are shown,

15 Figure 1 is a plan view of a reversible one-way reactance device embodying my invention;

Fig. 2 is a section on the line 2—2 of Fig. 1; and

20 Fig. 3 is a vertical sectional view showing another form.

Referring to the drawings in detail, and first to Figs. 1 and 2, the construction shown therein comprises a shaft 1 subject to oppositely-acting rotational impulses (one example of such a condition being in certain types of automobile transmission), a flexible strap 2 wrapped around said shaft, two anchorage members 3 and 4, one for each end of the flexible strap, and means for selectively rendering one or the other of said anchorage members effective, whereby with one setting of the selective means rotational impulses in one direction are rendered effective and rotational impulses in the opposite direction are rendered ineffective, and whereby with the opposite setting of the anchorage members the direction of effective and ineffective impulses is reversed.

Before describing in further detail the construction I will briefly outline the operation. If it is desired that the clockwise impulses only, as seen in Fig. 2, shall be effective (the counterclockwise impulses being ineffective), the circular cam 5 is moved to a position 45 which will hold the pivoted anchorage member 3 firmly in fixed position, leaving the other pivoted anchorage member 4 free to move to the right against the action of the coil tension spring 6. With this setting there 50 will be very little resistance to a clockwise im-

pulse, but a very great resistance to a counterclockwise movement, since the right-hand end of the strap 2 is firmly held and a moderate tension is exerted on the left-hand end of the strap.

If now it is desired that the direction of rotation be reversed and that counterclockwise impulses be effective, the circular cam 5 is moved to the dotted line position shown in Fig. 2, thus holding the left-hand pivoted anchorage member 4 firmly against the abutment 7, and permitting the right-hand anchorage member 3 to yield under the action of the flexible strap 2 against the tension of the coil spring 6.

Referring in further detail to the construction, the shaft may be provided with a series of longitudinally extending grooves 9 lying underneath the strap 2, the purpose of which is to break the oil film, thus increasing the clutching action. The ends of the straps may be secured to the pivoted abutment members by means of cap screws 10 or in any suitable manner. The pivoted abutment members may be pivotally mounted on parallel shafts 11.

The construction shown in Fig. 3 may be substantially the same as that just described, except that here two circular cams 12 are provided for controlling the position of the pivoted anchorage members 3 and 4 and selectively holding them in fixed position against the abutment members 13.

While I have shown but two embodiments of my invention, it is to be understood that various modifications thereof may be apparent to those skilled in the art without departing from the spirit and scope of this invention, and, therefore, the same is to be limited only by the scope of the prior art and the appended claims.

I claim:

1. In combination with a shaft, of means for rectifying oppositely acting rotational impulses acting thereon comprising a two-ended flexible member wrapped around said shaft, two anchorage means, one for each end of said flexible member, and means for selectively rendering one or the other of said anchorage means effective, whereby rota-

tional impulses in one direction are rendered effective and rotational impulses in the opposite direction are rendered ineffective, and vice versa.

- 5 2. In combination with a shaft, of means for rectifying oppositely acting rotational impulses acting thereon comprising a two-ended flexible member wrapped around said shaft, two anchorage means, one for each 10 end of said flexible member, and means for selectively rendering one or the other of said anchorage means effective, whereby rotational impulses in one direction are rendered effective and rotational impulses in the opposite 15 direction are rendered ineffective, and vice versa, and two yieldable means acting on the ends of said flexible member respectively for maintaining tension on the ends thereof to insure friction between the flexible member and the shaft.
- 20 3. In combination with a shaft, of means for rectifying oppositely acting rotational impulses acting thereon comprising a two-ended flexible member wrapped around said shaft, two anchorage means, one for each end 25 of said flexible member, and means for selectively rendering one or the other of said anchorage means effective, whereby rotational impulses in one direction are rendered effective and rotational impulses in the opposite 30 direction are rendered ineffective, and vice versa, each anchorage means comprising a pivoted member secured to the flexible member.
- 35 4. In combination with a shaft, of means for rectifying oppositely acting rotational impulses acting thereon comprising a two-ended flexible member wrapped around said shaft, two anchorage means, one for each 40 end of said flexible member, and means for selectively rendering one or the other of said anchorage means effective, whereby rotational impulses in one direction are rendered effective and rotational impulses in the opposite 45 direction are rendered ineffective and vice versa, each anchorage means comprising a pivoted member secured to the flexible member, said selective means comprising cam means acting on said pivoted member.
- 50

In witness whereof, I have hereunto subscribed my name.

ADIEL Y. DODGE.
